ANDERS H. BULL, OF BROOKLYN, NEW YORK.

ELECTRIC SIGNALING SYSTEM.

1,155,547.

Specification of Letters Patent.

Patented Oct. 5, 1915.

Application filed June 25, 1910. Serial No. 568,781.

To all whom it may concern:

Be it known that I, ANDERS H. BULL, a citizen of the United States, residing at No. 519 Eighth Avenue, Brooklyn, in the county 5 of Kings and State of New York, have invented certain new and useful Improvements in Electric Signaling Systems, of which the following is a specification.

My invention relates to an electric signaling system which is so constructed that a number of receivers, all connected to the same conductors, may be called selectively from one transmitting station. This is accomplished by using series of current impulses for operating the receivers and adjusting each individual receiver to a distinct combination of impulses.

A certain number of the impulses constituting a series are produced in a fixed 20 order, the time intervals between them being the same in all series. These impulses will be referred to in the following as "regular impulses". The remaining impulses, referred to as "special impulses", are produced so as to follow directly upon some of the regular impulses.

According to the number of special impulses contained in a series, and the way they are arranged relative to the regular 30 impulses, the form of the resulting series will be different. By varying the number and positions of the special impulses it is thus possible to produce series of various forms, the number of attainable forms increasing rapidly with the number of regular impulses used in the series.

Each individual receiver is made to respond to such special impulses only as are arranged in a distinct way, and by producing 40 series of different forms it is thus possible to send signals selectively to the different receivers.

Figure 1 shows, diagrammatically, a number of different forms of series, each made 45 up of six regular impulses, indicated by light cross strokes on a horizontal line, representing time, the special impulses being indicated by heavy cross strokes. Fig. 2 shows a transmitter connected to several 50 receivers, A, B, C, the last one of which is shown in a larger scale. Fig. 3 shows in a diagrammatic way the inside arrangement of the transmitter and Fig. 4 the inside arrangement of a receiver. Fig. 5 is an end 55 view of a receiver.

In the transmitter shown at the top of

Fig. 2 a contact brush 6 is supported by an arm 7 secured to the spindle 8. By throwing a lever 9 (Fig. 3) to the right, a pawl 10 pivoted to said lever will engage 60 a tooth on a ratchet wheel 11, which is geared to the spindle 8 through several gear wheels 12, as shown in Fig. 3. Upon releasing the lever 9, a spring 13 attached to an arm 13' secured to the spindle 9' of the 65 lever 9 will return the lever to its first position (Fig. 3), in which it is stopped by a pin 14. Thereby the arm 7 on spindle 8 has received one complete revolution, its speed being retarded and controlled by the 70 vane 15, shown in Fig. 3.

A curved bar 16 is provided with projections A, B, C, ... F, forming contact pieces. Other contact pieces G, H, I, ... M may be connected to the bar 16 by means of pegs 75 17. In the diagram according to Fig. 2 connections are thus made for the contact pieces G, I, M. The bar 16 is connected to one pole of the battery 18. The other pole and the brush 6 are connected to the 80 line wires 19 and 20 respectively. During the revolution of the arm 7 the brush 6 will ride over the contact pieces, and a series of impulses will be sent over the line wires, the impulses produced by the projections 85 A, B, C, etc., constituting the regular impulses of the series. The series thus produced is represented by 1 in Fig. 1.

In the receiver, as shown at the bottom of Fig. 2, a ratchet disk 21 is connected 90 to a clock-work 22 (Fig. 4), which is wound by means of a key 23. The disk 21 has, therefore, the tendency to rotate, but its rotation is normally prevented by a pawl 24, engaging one of the teeth on the disk. 95 When, however, the electromagnet 25 is energized by a current flowing through the line wires 19, 20, the pawl is withdrawn, permitting the disk 21 to rotate. Similarly as in the transmitter, the speed of the disk 100 21 is retarded by a vane 26, which is so adjusted that the disk will turn an angle corresponding to the distance between two of its teeth in slightly less time than it will take the brush 6 in the transmitter to cover 105 the distance between two of the projections A, B, C, etc.

The magnet 25 is connected through the line wires 19, 20 with the transmitter and when a series of impulses is sent from the 110 latter, the first regular impulse will release the disk 21. Before the next regular impulse

is sent, the disk has been stopped by the pawl 24. By the new impulse it is again released, and this operation is repeated for every regular impulse, so that, 5 when the arm 7 has completed its revolution, the disk 21 will also have made one complete revolution, the number of teeth on the disk corresponding to the number of projections on the bar 16. While the regular impulses 10 of the series will thus start the disk 21, the special impulses are produced while said disk is rotating.

Above the disk 21 is loosely mounted on the same spindle a smaller disk 27, having a 15 lug 28 which is pivotally connected through the rod 29 with a link 30. The other end of the latter is pivoted to the disk 21 and is rigidly connected to another link 31. Under the influence of a leaf spring 33, 20 bearing against the link 30, the smaller disk 27 tends to turn counter clock-wise relative to the disk 21, being, however, prevented from doing so by a number of hooks 34. These hooks hinge on pivots put through 25 holes 41 in the disk 27, their free ends engaging pins 35 on the disk 21. The hooks are pressed slightly against their pins by springs 42 attached to the disk 21. The distance of the pins 35 from the center of the 30 disk is gradually decreasing, as shown exaggerated, so that only one hook will engage its pin at a time. By disengaging one hook after the other from its pin, starting with the hook shown nethermost in the diagram 35 and finishing with the uppermost one, the disk 27 is released. The stepwise arrangement of the pins prevents the hooks that have been first disengaged from engaging their pins again.

40 In receiver C, the hooks are so arranged that their free ends will pass the point of a trigger 36, shortly after the disk 21 has been released by the first, third and sixth regular impulse, and while the transmitter brush 6 45 is riding over the contact pieces G, I, M. When the armature of the magnet is attracted, the trigger is pushed toward the center of the disk, in which position it will disengage any hook passing by, because the 50 disk 21 will keep on rotating while the end of the hook is caught by the trigger.

With none of the contact pieces G, H, I, etc., connected to the bar 16 in the transmitter, the armature of the receiver magnet, 55 after having released the disk 21, will be returned to its original position by the spring 37 before the hooks 34 reach the trigger 36, and they will, therefore, pass clear of it. If, however, the contact pieces G, I, M are 60 connected to the bar, as shown in the top view of Fig. 2, the first, third and sixth of the regular impulses are followed by a special impulse, and when, in receiver C, the hooks 34 pass the trigger 36 the armature 65 will again have been attracted. The trigger

will, therefore, disengage the hooks, thereby releasing the disk 27, which will turn relative to the larger disk, until the link 30 strikes the pin 38 on disk 21. By this movement the right hand end of the rod 29 is pushed out beyond the edge of the disk 21, in which position it will, during the further rotation of said disk, strike one end of a switch 39, throwing it over and thereby closing a bell circuit. Before the revolution of disk 21 is completed, the free end of the link 31 will strike a pin 40, fixed in the casing, whereby the disk 27 is returned to its former position relative to disk 21, in which position it will be again arrested by the hooks. A series of impulses as indicated in line 1, Fig. 1 will thus start the bell of receiver C ringing. A series as indicated in line 2 of Fig. 1 would have no such effect, for although the first and second of the special impulses have the same position as in the first series, the third special impulse has a different position, and while, therefore, two hooks will be disengaged, the third will pass clear of the trigger, and the disk 27 will not be released. 70 While receiver C is thus adjusted to series No. 1 it may easily be adjusted to other series by changing the arrangement of the hooks 34. If, for instance, the hook shown uppermost in the diagram is shifted to the one next below of the holes 41, the other hooks being left in the positions shown, then a hook would pass the trigger upon the first, third and fifth release of the disk 21, and the receiver would thus be adjusted to series No. 2. On the other hand it is obvious that the receiver C, if adjusted as shown, will respond to any series of impulses, in which the first, third and sixth regular impulse is followed by a special impulse, no matter whether the series in question contains other special impulses, as the latter will have no effect and, therefore, will not interfere with the action of the three special impulses first mentioned. This circumstance renders it 75 possible to call several receivers at the same time, which is often desirable. Thus a receiver adjusted to series 2 may be called simultaneously with the receiver C, by connecting to the bar 16 in the transmitter the contact pieces G, I, L, M, the resulting series 80 being represented by line 4 in Fig. 1. The number of contact pieces shown in the transmitter permits the selective calling of up to twenty receivers and, in a similar way, they 85 may all be called simultaneously by connecting up all the contact pieces G, H, I, etc., in the transmitter, the resulting series having 90 the form 5, Fig. 1.

The construction and mode of operating 95 the apparatus may be modified in several ways. Thus it is not necessary to completely interrupt the current between the impulses as a sufficient reduction of the current intensity will have the same effect.

I claim:

1. The combination with a line circuit, and a source of electric current, of a transmitter having means for producing a number of current impulses and, after any of said impulses, a further impulse, said impulses being of any polarity, a plurality of receivers, each receiver including signal operating means, a movable member operable by said impulses, selective means adapted to be positioned to engage said movable member for controlling said signal operating means, means also operable by impulses for controlling the position of said selective means relative to said movable member, the effect of said movable member upon said signal operating means depending on the position of said selective means at the time of operation of said movable member, 20 and a signal controlled by said signal operating means.

2. A selective signaling system including a line circuit, a source of electric current, a transmitter having means for producing a number of current impulses and, after any of said impulses, a further impulse, said impulses being of any polarity, a plurality of receivers, each receiver including signal controlling means, selective means controlling the operation of said signal controlling means, impulse operated means associated with said selective means and controlling the position thereof, an impulse controlled member adapted to coöperate with said selective means during certain prearranged positions, thereby causing said signal controlling means to be operated, and signaling means responding to a given number of operations of said signal controlling means.

3. A selective signaling system including a line circuit, a source of electric current, a transmitter having means for producing a number of current impulses and, after any of said impulses, a further impulse, a plurality of receivers, each receiver including a driven member, means operable by impulses for controlling the movement of said member, a second member having a plurality of connections with said driven member, a second means also operable by impulses for releasing said connections, said connections changing their position relative to said second means during the movement of said driven member, being releasable in distinct positions only, means for actuating said second member when all of said connections have been released, and signaling means controlled by said second member.

4. A selective signaling system including a line circuit, a source of electric current, a transmitter having means for producing a number of current impulses and, after any of said impulses, a further impulse, a plu-

rality of receivers, each receiver including a driven member, means for arresting said member in different positions, said arresting means being releasable by impulses, retarding means permitting said member, when free to move, to change its position at a given rate, signal controlling means moving with said member, means operable by impulses for controlling said signal controlling means, the effect of said impulse operated means upon said signal controlling means being dependent upon their relative position so as to permit said signal controlling means to respond to current impulses produced while said driven member is in certain given positions.

5. The combination with a line circuit and a source of electric current, of a transmitter having means for producing a number of regular current impulses and, after any of said impulses, a special impulse, a plurality of receivers, each receiver including a driven member, means releasable by impulses for arresting said member in different positions, retarding means permitting said member to change its position during a time period exceeding the duration of a special impulse, signal controlling means, selective means controlling said signal controlling means and moving with said driven member, a second means operable by impulses for controlling said selective means, said selective means being thus arranged relative to said second means as to be operable only while said driven member is moving from certain arrested positions to others, and a signal operable through said signal controlling means.

6. The combination with a line circuit and a source of electric current, of a transmitter having means for producing a number of current impulses and, after any of said impulses, a further impulse, a plurality of receivers, each receiver including a member automatically changing its position when released, means operable by impulses for controlling the movement of said member, signal controlling means, means controlled by impulses for controlling the operation of said signal controlling means, said impulse controlled means being under control of said member so as to make the operation of said signal controlling means dependent on the position assumed by said member upon the latter being released, and signaling means responding to a given number of operations of said signal controlling means.

7. A selective signaling system including a line circuit, a source of electric current, a contact bar provided with a set of contact pieces regularly spaced apart, a second set of contact pieces, means for connecting electrically any of the latter contact pieces to said contact bar, a brush adapted to slide

over both sets of contact pieces, a rotatable disk, a second disk rotating with the first disk and adapted to be rotated relative to said first disk, means for normally preventing such relative rotation, a signal adapted to be operated through said second disk, a pawl for arresting the two disks, and electromagnet adapted to release said pawl on being energized by current impulses produced by the first set of contact pieces, a trigger operated by said electromagnet and

adapted to release the means preventing the relative rotation of the two disks on the magnet being energized by current impulses produced by the second set of contact pieces. 15

In testimony whereof I affix my signature in presence of two witnesses.

ANDERS H. BULL.
